DRIVING HEAD FOR SUPPORT POSTS

Application filed May 20, 1931. Serial No. 538,730.

The present invention relates to a driving head for support posts, such as are used to support highway markers and similar signs. Such posts are usually of sheet metal formed into channel or other suitable shape to give 5 rigidity thereto.

It is common practice in the erecting of supporting posts of this nature to drive them into the ground, and to use a cast iron driving head with a curved slot in the lower side thereof, said slot being shaped to conform to the shape of the top of the post to be driven to receive the top edge of the supporting post in said slot to avoid disfiguring the top of 10 the post and to form a more suitable striking surface to receive the blows of a sledge with which the posts are driven into the ground.

The present type of driving caps are open 20 to several serious objections, namely, that they cannot satisfactorily be drop forged due to the nature of the slot in the lower face thereof, and their non-adaptability for use with different sizes of posts, and the weakening of the driving head caused by the slotting thereof.

Among the objects of my invention is the production of a driving cap which can be drop forged and which will have the strength 30 of a solid head, unweakened by any internal slotting, and which further is adapted for use with different sizes of posts.

In order to attain these objects, there is provided, a driving head having a solid upper portion and a pair of downwardly 35 extending fingers on the lower face of said head portion, said fingers being spaced apart to receive a portion of a formed, sheet metal post therein, the lower face of the head portion being adapted to rest on the upper edge 40 of the post to evenly distribute the force of a blow on the driving head over the upper edge of the post, the downwardly projecting fingers being positioned to prevent displacement of the driving head with respect to 45 the post and being adapted to receive different sizes of posts therebetween, the structure being designed so as to be capable of being produced by drop forging.

These and other features of the invention 50 will be more fully brought out in the follow-

ing description and the accompanying drawing, wherein:

Figure 1 is a view in front elevation of a driving head embodying the present invention.

Figure 2 is a side view of the structure shown in Figure 1; and

Figure 3 is a bottom view of the structure shown in Figures 1 and 2, a channeled post being indicated in position therein in dotted 60 lines.

Referring to the drawing in detail, the driving head comprises a top portion 1 having a flat lower surface 2 and preferably having the upper surface 3 thereof tapered inwardly, as illustrated, so as to centralize the force of the blows received by the device when driving a post into the ground. A substantially rectangular finger portion 4 extends downwardly from the center of one 70 side of the head portion 1 and is preferably formed integrally therewith. A second downwardly extending finger 5 also preferably formed integrally with the head portion, is spaced inwardly from the finger 4 75 a distance sufficient to permit the insertion between these members or fingers of the maximum thickness of material of which it is intended to fabricate the posts intended to be driven by the driving head. The inner, 80 downwardly extending finger 5 is of a width to fit interiorly of the smallest post which it is intended to drive with the present driving head, and the dimensions of the lower face 2 of the top portion 1 are such as to preferably 85 cover the top portion of the largest post which it is intended to drive with the device. A post 6, indicated in dotted lines in Figure 3, is of an intermediate size between the largest and smallest for which the cap is adapted.

It will be apparent to those versed in the art, that this structure may be readily fabricated by the process of drop forging. Therefore, the life of a device made in accordance with the present invention and produced by drop forging will be very much longer than that of the old type of slotted, cast iron driving head.

As will also be apparent, a much stronger and more effective driving head is secured by 100

reason of having downwardly extending fingers from a solid head adapted to hold the driving cap in position on the post to be driven instead of having the head itself slotted, as heretofore has been done, and that much greater adaptability of the device with respect to use with different sizes of posts is secured thereby.

We claim:

- 10 1. A driving cap for channeled metal posts, comprising a solid head portion, a finger member extending downwardly from one side of said head portion, a second finger member extending downwardly from the head portion a spaced distance inwardly from the first finger member, said finger members being spaced apart a distance sufficient to admit a side of the post, the width of the inner downwardly extending finger portion being of a size to fit within the channel of the post to be driven.
- 15 2. A driving cap of the class described, consisting of a solid driving head formed with a pair of downwardly projecting fingers, spaced apart to form an intermediate receiving space for a part of a post to be driven, one of the fingers being positioned from the other finger toward the center of the bottom of the driving head, for the purpose set forth.
